UNITED STATES PATENT OFFICE.

JAMES STANLEY, OF NEWARK, NEW JERSEY, ASSIGNOR TO LILLIAN LEMASSENA.

CARRIAGE-TOP-PROP BLOCK.

SPECIFICATION forming part of Letters Patent No. 296,240, dated April 1, 1884.

Application filed May 9, 1883. (No model.)

To all whom it may concern:

Be it known that I, JAMES STANLEY, a citizen of the United States, residing at Newark, in the county of Essex and State of New Jersey, have invented certain new and useful Improvements in Carriage Prop-Blocks and Means for Forming the Same; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to certain improvements in top-prop blocks, and to the process of producing the same, it having for its object the reduction of the cost of production and to increase the durability and improve the finish of the article produced.

The invention consists in the improved top-prop block constructed as set forth hereinafter, and finally embodied in the several clauses of the claims.

In the accompanying drawings, in which similar letters of reference indicate like parts in each of the several figures, Figure 1 illustrates an introductory step in the process of manufacturing a top-prop block. Fig. 2 is an end view of top-prop block after it has been wrapped. Fig. 3 shows the same after it has passed through a set of rollers. Fig. 4 illustrates said rollers and the process of pressing the top-prop blocks into shape; and Fig. 5 is a side elevation of a portion of a block, showing a series of tacks therein.

The top-prop blocks now in ordinary use, which have a similar contour, are formed of wood, rubber, and of other material, but are for various reasons defective. For example, the wooden blocks are extremely liable to shrink and split, and thus be rendered useless for the purpose. Where they have been made of rubber, the elastic nature of the same interferes with the retention of the lustrous finish, a japan coating upon the rubber soon cracking to such an extent as to make a material contrast between the block and the adjacent japanned parts of the vehicle. Furthermore, said rubber cannot practically be japanned, as

the japanning process requires a degree of heat that will cause the rubber to melt or become viscid. Thus the rubber block is not adapted to receive the high finish resembling that of the body of the carriage, such as the improved block possesses.

In carrying out my invention I wrap a strip or strips or scraps of leather, *a*, around a bar, *b*, as shown in Fig. 1, as many times as the desired size of block may require. After the leather has been wrapped several times, I insert a strip of rubber, *c*, or other elastic strip, either round, flat, or half-round, and then continue the wrapping until the full size is reached. One or both sides of the strip of leather is covered with paste or other adhesive substance, so that the wrappings, when pressed and dried, will unite and form one solid roll. After the leather has been wrapped or rolled around the bar, the roll is passed through the rollers, of the peculiar construction shown in Fig. 4, which rolls press the several parts or wrappings into intimate and continuous contact, the bar *b* acting to keep the shape of the longitudinal opening in the roll of wrappings.

The elastic strip may be dispensed with, if desired, although I prefer to retain the same in the top-prop, as it gives sufficient without an excess of elasticity.

When heretofore a solid rubber longitudinal ridge has been arranged on the block for the bow to engage with, a strap has been usually arranged to hold the bows in place and prevent damage liable to result from an excess of elasticity in the cushion formed by said rib. With my improved device such a strap is rendered unnecessary, for, although a certain amount of elasticity is provided by the peculiar arrangement of leather and rubber, not enough is supplied to cause the bows to be thrown into the air, to their damage.

The prop-blocks being formed as shown in Fig. 3, a patent-leather or hard-rubber finish may be applied to the surface of the block, to produce a solid, unbroken covering, with no seams or joints visible, as when ordinary patent-leather is sewed around a block. The exterior coating also cements any loose edges of the outer layers of leather, and makes a hard, durable, and finished block.

Tacks, as n , may be driven into the block, as indicated, to keep the parts together and to keep the ridge from spreading. After being driven, said tacks are covered by the finishing coating, and thus concealed from view.

Although the process and machine for producing the peculiar prop-blocks are described in this specification, I do not claim the same herein, as said process and machine form the subject-matter of a distinct application pending contemporaneously with this. The generic claim for the block composed of leather enwraps is also reserved, and is embodied in another contemporaneous application.

15 What I claim as my invention is—

1. A prop-block cylindrical in shape, with a longitudinal projecting ridge, d , thereon, formed of pieces of leather pressed and pasted into shape, and having a rubber core-piece, c ,

arranged in the projection thereof, substantially as and for the purposes set forth and shown.

2. In combination with the top-prop a , having the raised portion, d , the tacks n , arranged and operating substantially as set forth and shown.

3. In combination, the leather top-prop a , having the raised portion, d , a series of tacks, n , secured in said leather, and covered by a coating of patent-leather or hard-rubber finish.

In testimony that I claim the foregoing I have hereunto set my hand this 12th day of February, 1883.

JAMES STANLEY.
